MIDGET TOOTHBRUSH

Dandy J. Mayeux, Philadelphia, Pa.

Application November 14, 1941, Serial No. 419,095

2 Claims. (Cl. 15—133)

My invention relates to midget toothbrushes, and certain objects of the invention are to provide a miniature toothbrush whose handle and head are preferably made of one piece of cardboard or the like that is highly compressed and impregnated with some sort of water resisting substance so that it will be sufficiently stiff, strong and water-proof to withstand the strain and contact with water while brushing one's teeth for at least one time.

Other objects are to provide a toothbrush that is so cheaply constructed that it may be sold in slot vending machines, or in packages of a dozen or more and at such a low price that it may be discarded after one usage.

Further objects are to provide a toothbrush made of one piece of cardboard or the like, that is so designed that it may be folded along predetermined lines to form a flat reenforced head backing upon which bristles are secured, and a hollow handle in which sufficient tooth powder or paste is contained for cleaning the teeth at least one time.

In the drawing:

Figure 1 is a top plan view showing the pattern or design in one flat piece of cardboard or the like for forming the head and handle of the toothbrush;

Fig. 2 is a bottom plan view showing the head extension flap and the head side flaps folded and secured to form the reenforced head of the toothbrush;

Fig. 3 is a view in longitudinal vertical section of the completely formed toothbrush with bristles attached to its head and its hollow handle filled with tooth powder or paste; and

Fig. 4 is a view in transverse vertical section taken on a broken line 4—4 of Fig. 3.

Referring in detail to the drawing wherein like reference numerals designate like parts in the several views, the flat design of the device, which is preferably made of a single piece of cardboard or the like, consists in part of an extension head flap 5 and two oppositely disposed side head flaps 6 and 7, all of which parts collectively form the reenforced head portion of the brush when properly folded and secured as hereinafter described.

The handle portion of the brush consists of two oppositely disposed handle side flaps 8 and 9, and the back of the brush, as designated by the numeral 10, is formed by folding or creasing these side flaps along lines 11, indicated by dashes in Figs. 1 and 2, and which lines extend in parallel relation from the side edges of the extension

head flap 5 for the full length of the head and handle portions of the brush.

The side head flaps 6 and 7 are separated from the side handle flaps 8 and 9 by transverse slits 12 extending respectively from the edges of the cardboard to the dash lines 11, as shown in Fig. 1 of the drawing. These slits allow the side head and handle flaps to be folded and secured separately as will be understood. An end flap 13 may be provided for sealing the rear end of the hollow handle when the brush is completely formed as more fully hereinafter set forth.

The first step in forming the toothbrush, shown in Fig. 2 of the drawing, consists in folding the head extension flap 5 over against the back 10, pressing it flat, and preferably though not necessarily securing it thereto by means of water-proof glue or other water-proof adhesive. Next, the side head flaps 6 and 7 are folded over along the lines 11, pressed flat, and preferably secured to the extension flap 5 by means of water-proof adhesive. These two steps form the head backing of the brush.

The handle of the brush is formed by folding or creasing the handle flaps 8 and 9 along the lines 11. These handle flaps are then bent around until their longitudinal edge portions overlap each other, as shown in Figs. 3 and 4, and are secured together by means of water-proof adhesive to provide a somewhat conical longitudinal chamber 14 within the handle. This can best be done by bending the handle flaps around upon a form of the proper shape.

The head of the brush is completed by securing bristles 15 thereto. These bristles may be stapled through, or otherwise secured to a fabric or other backing 16, and this bristle backing is secured to the flat folded head flaps 6 and 7 by means of water-proof adhesive. The last step consists in filling the handle chamber 14 with tooth powder, paste or other dentifrice, as shown in Figs. 3 and 4 of the drawing, and then sealing the end flap 13. This flap may be sealed by means of water-proof adhesive and the application of liquid wax to make it water-proof, or a small piece of cellophane paper may be used in place of the flap 13. This sealing flap is provided with a small projecting point which may be used in breaking the seal.

In the formation of the head portion of the brush, it will be noticed in Figs. 2 and 3 that the inner end portion of the head extension flap 5 extends inwardly beyond the slits 12 in its folded position, and that the inner end portion of the folded handle flaps 8 and 9 is flatly se-

cured thereto. It will also be observed that the inner or transverse edges of the head flaps 6 and 7 and of the bristle backing 16 abut against the double thickness of the inner end of the handle flaps 8 and 9. When said portions are secured in these positions, a strongly reenforced head is provided. Water-proof adhesive is used in securing all parts, and the entire cardboard is stiff and strong and is impregnated with water resisting substance so that the brush may be used for sufficient time to clean the teeth at least one time without bending or collapsing.

It will now be apparent that I have provided a miniature toothbrush of strong construction which can be manufactured and sold at such low cost that it may be thrown away after one usage. It may be sold by means of vending machines, or in packages and is very handy for use by men in the naval and military service, house guests, and when traveling. While I have described the brush as being made of cardboard, it will be understood that other inexpensive material may be used in its construction. I also preferably use mohair or rug-like material for the bristles to reduce the cost of the brush.

I claim:

1. A toothbrush comprising a handle and head portion formed from an elongated piece of stiff cardboard or the like, scored by spaced lines, lengthwise thereof, and setting off a central back panel and opposite side flaps the length of the piece; said flaps being cut by aligned slits perpendicular to the back panel and thereby setting off the brush head at one end of the handle portion; there also being an extension portion of said cardboard integral with the back panel of the head portion corresponding in width

thereto, and folded back and flatly against the under side of said back panel; said flap portions along the opposite side of the head portion being folded inwardly to overlap the back-turned extension portion, and said flaps of the handle portion being folded inwardly to cooperate with said back panel to form a handle body, and a brush applied and secured to said inturned flaps of said head portion.

- 5 2. A toothbrush comprising a handle and head portion formed from an elongated piece of stiff cardboard or the like scored by spaced lines lengthwise thereof, and setting off a central back panel and opposite side flaps the length of the piece; said flaps being cut by aligned slits 10 perpendicular to the back panel and thereby setting off the brush head at one end of the handle portion; there also being an extension portion of said cardboard integral with the back panel of the head portion corresponding in width thereto, and folded back and flatly against the under side of said back panel; said flap portions along the opposite side of the head portion being folded inwardly to overlap the back turned extension portion; and said flaps of the handle portion being folded inwardly to engage along their edges and to cooperate with said back panel to form a hollow closed handle body, and a brush applied and secured to said inturned flaps of the said head portion; said hollow handle body being closed at the head end, and there being a flap integral with the back panel serving as a closure for the outer end of the handle whereby to adapt it for the holding of a dentifrice.
